UNITED STATES PATENT OFFICE

140,466

DESIGN FOR AN OVERHEAD CABLE SUPPORT FOR BULLDOZERS OR THE LIKE

George E. Miller and Robert N. Bennett, Findlay, Ohio, assignors to The Buckeye Traction Ditcher Company, Findlay, Ohio, a corporation of Ohio

Application August 5, 1944, Serial No. 114,751

Term of patent 14 years

(Cl. D14—3)

To all whom it may concern:

Be it known that we, George E. Miller and Robert N. Bennett, citizens of the United States and residents of Findlay, Hancock County, Ohio, have invented a new, original, and ornamental Design for an Overhead Cable Support for Bulldozers or the like, of which the following is a specification, reference being had to the accompanying drawings, forming a part thereof.

In the drawings:

Figure 1 is a front elevational view of the front end portion of the overhead cable support;

Figure 2 is a rear elevational view of the rear end portion of the support;

Figure 3 is a side elevational view of the rear end portion shown in Figure 2 with the cable guide table broken away;

Figure 4 is a top plan view of the portions shown particularly in Figures 2 and 3; and

Figure 5 is a front perspective view of the overhead cable support.

We claim:

The ornamental design for an overhead cable support for bulldozers or the like, as shown.

GEORGE E. MILLER.
ROBERT N. BENNETT.
